UNITED STATES PATENT OFFICE.

CHARLES W. PALMER, OF CLEVELAND, OHIO.

IMPROVEMENT IN BRUSHES.

Specification forming part of Letters Patent No. 139,474, dated June 3, 1873; application filed May 5, 1873.

To all whom it may concern:

Be it known that I, CHARLES W. PALMER, of Cleveland, in the county of Cuyahoga and State of Ohio, have invented a new and useful Brush for Hats, Clothes, and Shoes, with a mirror combined, of which the following is a specification:

This invention relates to a brush, composed of fine plush on one side and Brussels carpet on the other side, also having a small mirror on one side at the end. The plush side is adapted for brushing silk-hats, velvets, and similar fabrics. The carpet side is adapted for brushing coarser fabrics of clothing and shoes. This brush is intended as a convenient article to be carried in the pocket by travelers, tourists, &c., for use on cars, stations, or other places where toilet conveniences cannot be had.

In the accompanying drawing, Figure 1 is an edge view; Fig. 2 is the carpet side, and Fig. 3 is the plush side of my improved brush.

A is a straight strip of suitable wood, of dimensions convenient for carrying in a person's pocket, on one side of which is attached a piece of plush, B, extending nearly the whole length of the strip A. D is a small mirror, also secured to the wood strip A in a suitable manner. C is a piece of Brussels car-

peting, secured to the opposite side of the wood A. These fabrics are secured with glue, and are also secured with fine-wire bands, E, to prevent the ends from getting loose by wear or otherwise.

This combined brush, constructed in this manner, may be conveniently carried in the side-pocket, and takes up but very little room, and is very useful for brushing off dust from silk-hats, &c., while traveling; the carpet side, being stiffer, is very convenient for removing mud or dust from the bottoms of pants and from shoes. The glass is also a very desirable and convenient article in case one gets dirt or specks of cinder in the eyes while traveling. The brush is easily kept clean by striking it briskly against any hard substance, which loosens the dirt in the brush, and it falls out.

I claim—

The strip A, plush B, carpet C, mirror D, and wire-bands E, all combined and arranged as described, and for the purpose set forth.

CHARLES W. PALMER.
